UNITED STATES PATENT OFFICE.

HARRY O. RUGH, OF CHICAGO, ILLINOIS, ASSIGNOR TO WESTERN TELEGRAPH COMPANY, OF CHICAGO, ILLINOIS, A CORPORATION OF SOUTH DAKOTA.

TELEGRAPH SYSTEM.

SPECIFICATION forming part of Letters Patent No. 757,503, dated April 19, 1904.

Application filed August 31, 1903. Serial No. 171,398. (No model.)

To all whom it may concern:

Be it known that I, HARRY O. RUGH, a citizen of the United States, residing at Chicago, in the county of Cook and State of Illinois, have invented a certain new and useful Improvement in Telegraph Systems, of which the following is a full, clear, concise, and exact description, reference being had to the accompanying drawings, forming a part of this specification.

My invention relates to telegraphy, and has for its object the provision of an improved system and apparatus whereby wave-form current as alternating current of suitably high frequency may be employed in effecting telegraphic signals. By means of my invention the same telegraphic circuit may be simultaneously employed for both direct and wave-form telegraphic currents. To this end I have devised apparatus at the stations employing the instruments to be operated by wave-form current that will effectively respond to the wave-form current at the receiving-stations and which will also be operated at the sending-station without unduly weakening the current, the system enabling the substantially uniform operation of the sounders at the receiving and sending stations.

My invention will be fully pointed out in the following specification and claims, and illustrated in the accompanying drawings, in which—

Figure 1 illustrates the preferred embodiment of my invention. Fig. 2 is a view in elevation of the line-relay.

Like parts are indicated by similar characters of reference in the views.

I have indicated a transmission-line 1 common to a plurality of telegraph-stations 2, 3, 4, 5, 6, 7, and 8. It is understood that the number of each kind of stations may be varied. At stations 2, 5, and 8 are indicated ordinary telegraphic outfits, each including a line-relay 9, normally energized by a battery 10, a sending-key 11, and a sounder 12, whose magnet is included in a local circuit, there being but one local circuit to each of the stations 2, 5, and 8. If the line-relays are not of sufficient

impedance to prevent the wasteful passage of wave-form current that I employ to operate the apparatus at stations 3, 4, 6 and 7, impedance-coils 13, preferably of low ohmic resistance, may be inserted in the line. At station 5 a condenser 14 may be employed to permit the passage of the alternating telegraphic current about the line-relay at this station which is to be operated only by direct or straight current.

Stations 3, 4, 6, and 7 are preferably connected with the main line by branches 15, preferably multiplied from the main line and preferably containing condensers 16.

Each line-relay 17 includes a permanently-magnetized core 18, whose winding may be, say, of one hundred ohms resistance and subject to the wave-form or alternating current impressed upon the main line. The soft-iron vibratory diaphragm 19 of said relay constitutes a vibratory contact element, said diaphragm preferably performing the functions of an armature and a circuit-contact. The diaphragm is located before the magnet of the relay and has a movable or traveling contact element 20 resting against the same. The contact 20 is preferably mounted upon a pivoted arm 21 and is given physical inertia by having a weight 22 added to the arm. Any of the current caused by the battery 10 that may find path through the condensers 16 to the relays 17 will fail to cause effective operation of said relays because the contact 20 is maintained in engagement with the diaphragm not only by reason of the weighted arm, but also by the adjusting-spring 23, that serves to regulate the degree of pressure of the contact against said diaphragm. Wave-form current of sufficiently high frequency, however, will cause separation between the diaphragm and said contact, and thereby open the subsidiary or local-relay circuit 24. This subsidiary sounder-controlling circuit I consider to be an important feature of my system, as it enables the highly satisfactory use of alternating current for telegraphic purposes. It includes a battery 25 and a local relay 26, whose armature 27 is normally attracted to

90
95

maintain the sounder-circuit 28 open. This sounder-circuit includes the sounder-magnet 29, the battery 30, and the armature 27 with its back contact 32. When the relay-contacts 19 and 20 are separated under the conditions specified, the sounder-circuit is closed positively to cause a sound by the attraction of the armature. As a preferable source or supply of telegraphic current for use at each of the stations 3, 4, 6, and 7, I employ a mechanically-driven alternating-current generator 33, driven by some suitable form of prime mover, as an electric motor 34, at a sufficiently high speed. In the form shown one terminal brush of this generator is grounded, while the other is connected with an alternate contact 35 of the sending-key or switch 36, which key is connected with the conductor 15 through the helix of the line-relay. The sending-key is normally grounded through the normal contact 37 thereof, furnishing a direct path from the line-relay to the said key and ground.

The key 36 is desirably centrally pivoted and in this instance has a second alternate contact 38, that constitutes a normally free terminal of a branch conductor containing choking resistance 39, that in the circuit arrangement shown at station 3 is preferably of very low ohmic resistance—say one ohm of moderate apparent resistance or inductance. The resistance 39 at station 7 is a condenser with, say, a capacity of one-tenth a microfarad. When the key 36 is depressed, the helix of the line-relay and the resistance 39 are included in parallel paths. The less the resistance 39 the less the current from the alternating-current generator passing through the line-relay at the sending-station. By making said resistance adjustable, as by the means indicated, the exact proportion of the current from the generator at the sending-station that is to pass through the line-relay may be selected. In other words I have provided subsidiary circuit connections defining a path for a portion of the telegraphic current at the sending-station through the line-relay thereat and an additional path for said current that is independent of the line-relay.

The purpose of the resistance is to distribute the current at a sending-station, so that a portion will pass through the line-relay to operate the sounder at the sending-station, and the balance will pass over the line to operate the relay and sounder at a receiving-station.

It is obvious that the number of generators may be reduced, as the presence of conductors carrying the wave-form current is only necessary as a supply at each station.

It is obvious that changes may readily be made in the system and apparatus of the embodiment of my invention illustrated without departing from the spirit of the invention.

Having thus described my invention, I claim

as new, and desire to secure by Letters Patent, 65 the following:

1. A system of telegraphy comprising a transmission-line uniting a plurality of telegraph-stations; a supply of wave-form current at each station, a line-relay at each station comprising a permanent magnet as a core for the helix of the relay, a vibratory contact element actuated by the magnet of the relay, and a traveling contact element possessing inertia and normally resting against said vibratory contact element but separable therefrom through the agency of wave-form current impressed upon the relay; telegraphic sounder apparatus controlled by the contacts of each relay, sending-key mechanism at each station 80 for associating the current-supply thereat with said line, said key being connected with the relay and having a normal contact included in the normal circuit of the relay and two alternate contacts, one constituting a terminal 85 of said supply, and a conductor containing resistance to the current from said supply having one terminal in association with the line and the other in the remaining alternate contact of said key, substantially as described. 90

2. A system of telegraphy comprising a transmission-line uniting a plurality of telegraph-stations; a supply of wave-form current at each station, a line-relay at each station comprising a permanent magnet as a core 95 for the helix of the relay, a vibratory contact element actuated by the magnet of the relay, and a traveling contact element possessing inertia and normally resting against said vibratory contact element but separable therefrom 100 through the agency of wave-form current impressed upon the relay; telegraphic sounder apparatus controlled by the contacts of each relay, sending-key mechanism at each station for associating the current-supply thereat 105 with said line and a conductor containing resistance to the current from said supply and brought into and out of parallel relation with said relay by said key or switching mechanism, substantially as described. 110

3. A system of telegraphy comprising a transmission-line uniting a plurality of telegraph-stations; a supply of wave-form current at each station, a line-relay at each station including a vibratory contact element actuated by the magnet of the relay, and a traveling contact element possessing inertia and normally resting against said vibratory contact element but separable therefrom through the agency of wave-form current impressed 120 upon the relay; telegraphic sounder apparatus controlled by the contacts of each relay, sending-key mechanism at each station for associating the current-supply thereat with said line, said key being connected with the relay and having a normal contact included in the normal circuit of the relay and two alternate contacts, one constituting a terminal of said 125

supply, and a conductor containing resistance to the current from said supply having one terminal in association with the line and the other in the remaining alternate contact of said key, substantially as described.

4. A system of telegraphy comprising a transmission-line uniting a plurality of telegraph-stations, a supply of wave-form current at each station, a line-relay at each station including a vibratory contact element actuated by the magnet of the relay, and a traveling contact element possessing inertia and normally resting against said vibratory contact element but separable therefrom through the agency of wave-form current impressed upon the relay; telegraphic sounder apparatus controlled by the contacts of each relay, sending-key mechanism at each station for associating the current-supply thereat with said line and a conductor containing resistance to the current from said supply and brought into and out of parallel relation with said relay by said key or switching mechanism, substantially as described.

5. A system of telegraphy comprising a transmission-line uniting a plurality of telegraph-stations, a supply of wave-form current at each station, a line-relay at each station comprising a permanent magnet as a core for the helix of the relay, a vibratory contact element actuated by the magnet of the relay, and a traveling contact element possessing inertia and normally resting against said vibratory contact element but separable therefrom through the agency of wave-form current impressed upon the relay; telegraphic sounder apparatus controlled by the contacts of each relay, sending-key mechanism at each station for associating the current-supply thereat with said line and subsidiary circuit connections governed by said switching mechanism and constituting a path for a portion of the current through the line-relay at the sending-station and an additional path from the supply toward the main line independent of said relay, substantially as described.

6. A system of telegraphy comprising a transmission-line uniting a plurality of telegraph-stations, a supply of wave-form current at each station, a line-relay at each station including a vibratory contact element actuated by the magnet of the relay, and a traveling contact element possessing inertia and normally resting against said vibratory contact element but separable therefrom through the agency of wave-form current impressed upon the relay; telegraphic sounder apparatus controlled by the contacts of each relay, sending-key mechanism at each station for associating the current-supply thereat with said line, and subsidiary circuit connections governed by said switching mechanism and constituting a path for a portion of the current through the line-relay at the sending-station and an addi-

tional path from the supply toward the main line independent of said relay, substantially as described.

7. A system of telegraphy comprising a transmission-line uniting a plurality of telegraph-stations; a supply of wave-form current at each station, a line-relay at each station comprising a permanent magnet as a core for the helix of the relay, a vibratory contact element actuated by the magnet of the relay, and a traveling contact element possessing inertia and normally resting against said vibratory contact element but separable therefrom through the agency of wave-form current impressed upon the relay; a telegraphic sounder at each station; a circuit at each station controlling the sounder thereat and normally closed through the contacts of the relay, a sending-key mechanism at each station and circuit connections whereby a portion only of the telegraphic current impressed at a sending-station is directed through the line-relay to operate the sounder at the sending-station, substantially as described.

8. A system of telegraphy comprising a transmission-line uniting a plurality of telegraph-stations; a supply of wave-form current at each station, a line-relay at each station including a vibratory contact element actuated by the magnet of the relay, and a traveling contact element possessing inertia and normally resting against said vibratory contact element but separable therefrom through the agency of wave-form current impressed upon the relay; a telegraphic sounder at each station; a circuit at each station controlling the sounder thereat and normally closed through the contacts of the relay, a sending-key mechanism at each station and subsidiary circuit connections thrown into circuit by the sending-key or switching mechanism when operated whereby a portion only of the telegraphic current impressed at a sending-station is directed through the line-relay to operate the sounder at the sending-station, substantially as described.

9. A system of telegraphy comprising a transmission-line uniting a plurality of telegraph-stations; a supply of wave-form current at each station, a line-relay at each station comprising a permanent magnet as a core for the helix of the relay, a vibratory contact element actuated by the magnet of the relay, and a traveling contact element possessing inertia and normally resting against said vibratory contact element but separable therefrom through the agency of wave-form current impressed upon the relay; a telegraphic sounder at each station; a circuit at each station controlling the sounder thereat and normally closed through the contacts of the relay, a sending-key mechanism at each station and subsidiary circuit connections thrown into circuit by the sending-key or switching mechan-

ism when operated whereby a portion only of the telegraphic current impressed at a sending-station is directed through the line-relay to operate the sounder at the sending-station, 5 substantially as described.

10. A system of telegraphy comprising a transmission-line uniting a plurality of telegraph-stations; a supply of wave-form current at each station, a line-relay at each station 10 comprising a permanent magnet as a core for the helix of the relay, a vibratory contact element actuated by the magnet of the relay, and a traveling contact element possessing inertia and normally resting against said vibratory contact element but separable therefrom 15 through the agency of wave-form current impressed upon the relay; a local circuit at each station including the contacts of said relay; a local relay in each local circuit; a telegraphic sounder at each station; a normally open circuit containing each sounder; and a switch controlled by each local relay operating to close its sounder-circuit when operated upon the energization of said line-relay, substantially 20 as described.

11. A system of telegraphy comprising a transmission-line uniting a plurality of telegraph-stations; a supply of wave-form current at each station, a line-relay at each station 30 comprising a vibratory contact element actuated by the magnet of the relay, and a traveling contact element possessing inertia and normally resting against said vibratory contact element but separable therefrom through 35 the agency of wave-form current impressed upon the relay, a local circuit at each station including the contacts of said relay; a local relay in each local circuit; a telegraphic sounder at each station; a normally open circuit containing each sounder; and a switch controlled by each local relay operating to close its sounder-circuit when operated upon the energization of said line-relay, substantially as described.

40. 12. A system of telegraphy comprising a transmission-line uniting a plurality of telegraph-stations; a supply of wave-form current at each station, a line-relay at each station comprising a permanent magnet as a core 40 for the helix of the relay, a vibratory contact element actuated by the magnet of the relay, and a traveling contact element possessing inertia and normally resting against said vibratory contact element but separable therefrom 45 through the agency of wave-form current impressed upon the relay, a telegraphic sounder at each station; a circuit at each station control-

ling the sounder thereat and normally closed through the contacts of the relay, a sending-key or switching mechanism at each station 60 and means whereby the wave-form current at a sending-station effects the operation of the sounder at that station, substantially as described.

13. A system of telegraphy comprising a transmission-line uniting a plurality of telegraph-stations; a supply of wave-form current at each station; a line-relay at each station comprising a permanent magnet as a core for the helix of the relay, a vibratory contact 70 element actuated by the magnet of the relay, and a traveling contact element possessing inertia and normally resting against said vibratory contact element but separable therefrom through the agency of wave-form current impressed upon the relay; a circuit at each station including said elements, a telegraph-sounder controlled by said circuit and means whereby the outgoing wave-form current at 75 a sending-station will effect the operation of the telegraphic sounder at said station, substantially as described.

14. A system of telegraphy comprising a transmission-line uniting a plurality of telegraph-stations; a supply of wave-form current at each station; a line-relay at each station comprising a permanent magnet as a core 80 for the helix of the relay, two contact elements normally in engagement controlled by the line-relay; a circuit at each station including said elements, a telegraph-sounder controlled by said circuit and means whereby the outgoing wave-form current at a sending-station will effect the operation of the telegraphic sounder at said station, substantially as described.

15. A system of telegraphy comprising a transmission-line uniting a plurality of telegraph-stations; a supply of wave-form current at each station; a line-sound-controlling 90 magnet or relay at each station comprising a permanent magnet as a core for the helix of the relay, key sending mechanism, and circuit connections to define at a sending-station a path for a portion of the telegraphic current 100 through said line-relay and a path for a portion of the current to the telegraph-line, substantially as described.

In witness whereof I hereunto subscribe my name this 29th day of August, A. D. 1903. 110
